UNITED STATES PATENT OFFICE.

LLOYD V. LEWIS, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

1,373,086.

Specification of Letters Patent. Patented Mar. 29, 1921.

Application filed November 12, 1919. Serial No. 337,389.

To all whom it may concern:

Be it known that I, LLOYD V. LEWIS, a citizen of the United States, residing at Wilkinsburg, in the county of Allegheny and State of Pennsylvania, have invented certain new and useful Improvements in Railway-Traffic-Controlling Apparatus, of which the following is a specification.

My invention relates to railway traffic controlling apparatus of the type wherein traffic governing means located on a railway car or train is controlled by energy received from the track rails.

One object of my invention is the provision of a system of this character wherein three indications may be given on the car or train with vehicle governing current of one character only in the track rails, and I accomplish this object by means of impulse devices such as permanent magnets in the trackway which are effective to influence the governing apparatus on the car or train only in the absence of the vehicle governing current.

I will describe certain forms of apparatus embodying my invention, and will then point out the novel features thereof in claims.

In the accompanying drawings, Figure 1 is a diagrammatic view showing one form of trackway apparatus embodying my invention. Fig. 2 is a diagrammatic view showing one form of vehicle carried apparatus embodying my invention and adapted for coöperation with the trackway apparatus shown in Fig. 1. Fig. 3 is a view showing a modified form of vehicle carried apparatus also embodying my invention and also adapted for coöperation with the trackway apparatus shown in Fig. 1. Fig. 4 is a view showing a modified form of trackway apparatus adapted for use on a railway having non-positive control territory as well as positive control territory. Fig. 5 is a view showing a modified form of vehicle carried apparatus adapted for coöperation with the trackway apparatus shown in Fig. 4 and also embodying my invention.

Similar reference characters refer to similar parts in each of the several views.

Referring first to Fig. 1, the reference characters 1 and 1^a designate the track rails of a railway car over which traffic normally moves in the direction indicated by the arrow. These rails are divided by insulated joints 7 into a plurality of blocks, of which only two complete blocks A—B and B—C are shown in the drawing.

Each block is provided with a track circuit comprising as usual the track rails of 60 the block, a source of current connected across the rails at the exit end of the block, and a track relay connected across the rails at the entrance end of the block. As here shown, the source of current for each track 65 circuit is a battery designated by the reference character D with an exponent corresponding to the particular location, this battery being reversibly connected with the rails by a pole-changer designated P with 70 the same exponent, and operated as herein-after explained. The track relay for each block is designated H with an exponent corresponding to the location, each of these relays, of course, being adapted for operation by direct current. Each track relay is of a polarized type, comprising two neutral armature contacts 2 and 8, and a polarized armature contact 4. It follows, of course, that the polarized contact 4 will be swung 80 in one direction or the other according as the pole-changer for the corresponding track circuit is in one position or the other, and that the neutral contacts 2 and 8 of each relay will be closed or open according as 85 the relay is energized or deenergized.

Located adjacent the entrance end of each block is a roadside signal designated by the reference character S with an exponent corresponding to the location. Each of these 90 signals, as here shown, is of the semaphore type adapted to indicate "stop", "caution" or "proceed", according as the semaphore is in the horizontal, the inclined or the vertical position. Each signal is controlled by the 95 track relay for the corresponding block through the medium of a caution indication circuit and a proceed indication circuit. Considering S^B, for example, the caution indication circuit is from one terminal B of a 100

suitable source of current such as a battery, through the neutral contact 2 of relay H^B , wire 3, and the operating mechanism of signal S^B to the other terminal O of the same 5 source of current. The proceed indication circuit for this signal (shown open in the drawing) is from battery terminal B, through contact 2, polarized contact 4, wire 5, and the operating mechanism of signal 10 S^B , to the other battery terminal O. This proceed indication circuit is closed only when polarized contact 4 is swung to the left, and this occurs only when the relay H^B is supplied with current of what I will term 15 "normal" polarity. When the relay is supplied with current of the opposite or "reverse" polarity, contact 4 is open as shown, so that the signal indicates caution.

The pole-changer P, which is included in 20 each track circuit, is operated by the signal S for the block next in advance, and in such manner that the polarity of the current supplied to the track circuit is normal when the signal indicates proceed or caution, and 25 reverse when the signal indicates stop.

The operation of the apparatus thus far described is in accordance with usual and 30 standard practice, and hence no explanation is necessary. As shown in the drawing, the 35 block to the right of location C is occupied by a vehicle V', so that signal S^c indicates stop, signal S^B indicates caution, and signal S^A indicates proceed.

For each block I have provided means for 35 connecting a source of alternating vehicle governing current across the rails at the exit end of the block in series with the track battery for the block. As here shown, this is accomplished by a transformer designated 40 by the reference character T with an exponent corresponding to the location, the secondary of which is included in the connection between the lower track rail 1 and the pole-changer P. The primary of each 45 transformer T is at times connected with a transmission line E, which is supplied with alternating vehicle governing current by a suitable generator F. The primary circuit of each transformer T includes the neutral 50 contact 8 of the track relay for the block next in advance, so that vehicle governing current is supplied to the rails of each block when the track relay for the block next in 55 advance is energized, but not when such track relay is deenergized. In other words, this current is supplied to each block only when the block next in advance is unoccupied.

In accordance with usual practice, a non-inductive resistance 6 is interposed in the 60 connection between the track 1 and the secondary of transformer T to limit the current drawn from this transformer and from the battery D when a car or train is near the 65 exit end of the block.

Each block is provided with an impulse device M, located in the trackway at least at maximum braking distance from the exit end of the block for trains running at a "medium" speed which I will assume to be 70 35 miles per hour. Each block is preferably provided with a second impulse device M^a , located at the exit end of the block and in alignment with the magnets M. Each of these impulse devices, as here shown, is a 75 permanent magnet, although other forms of devices may be used if desired. If magnets are used, it is, of course, evident that constantly energized electromagnets could be substituted for the permanent magnets, although permanent magnets are preferred on account of their greater reliability and on account of the fact that they require no 80 supply of energy.

Referring now to Fig. 2, the reference 85 character V designates a vehicle, such as a car or train, which is here represented by an axle and pair of wheels. This vehicle carries two laminated soft iron cores 9 and 9^a , mounted in advance of the forward axle and 90 located over the two track rails 1 and 1^a , respectively. Each of these cores is U-shaped, with its legs pointing downwardly, and each core is disposed transversely with respect to the rail. The two cores 9 and 9^a are provided with windings 10 and 10^a , respectively. It is apparent, therefore, that when alternating current flows in either rail, part of 95 the magnetic lines of force surrounding such rail will pass through the core which is directly over the rail, and so will induce an alternating potential in the coil carried by such core.

The two coils 10 and 10^a are included in 100 series in a receiving circuit a , which circuit 105 also includes a condenser 16. The two coils are so connected in this circuit that the potentials induced in these coils by an alternating current flowing in opposite directions in the two rails are additive, so that 110 the vehicle governing current in the track rails will cause an alternating current to flow in circuit a . The coils 10 and 10^a are so wound as to have high inductance while the condenser 16 has a comparatively small capacity, and these parts are so adjusted that 115 circuit a is tuned to resonance at the frequency of the vehicle governing current; it follows, therefore, that condenser 16 will be charged to a comparatively high potential 120 by the comparatively feeble current induced in circuit a by the vehicle governing current in the track rails. This potential, 125 is however, too feeble to reliably actuate traffic controlling apparatus of a rugged character, hence I have provided suitable amplifying apparatus, which, in the form here shown, comprises two electron tubes K' and K^a . Each of these tubes (see tube K') 130 comprises a vacuum bulb 11 containing a

filament 12, a plate 14, and a grid 13 interposed between the filament and the plate. The filament 12 is constantly heated by a battery 15.

5 The grid of amplifier K' is excited by the potential in circuit a across the terminals of condenser 16, and the plate circuit of this amplifier includes a direct current generator G and the primary of a transformer J' . The secondary of this transformer energizes the grid circuit for amplifier K^2 , and the plate circuit of the latter amplifier includes the generator G and the primary of a transformer J^2 . The alternating current 10 induced in the secondary of transformer J^2 is transformed into pulsating direct current by a rectifier L and is used to energize a relay R , which I will term the continuous control relay. It will be seen, therefore, 15 that relay R will be energized or not, according to whether or not the rails of the block occupied by the vehicle are supplied with vehicle governing current.

20 Located also on the vehicle V is a second relay N , which I will term the medium speed relay. This relay is provided with a pick-up circuit which passes from a battery 17, through wire 18, front contact 19 of relay R , wire 20, and winding of relay N 25 to battery 17. It will be seen, therefore, that relay N is closed as long as relay R is closed. Relay N is provided with a holding circuit which passes from the battery 17, through wire 21, coil 22, wire 23, front 30 contact 24 of relay N , wire 25, and winding of relay N to battery 17. Coil 22 is located 35 on a core 26 of magnetizable material which is mounted on the vehicle V in such position as to pass in close proximity to the trackway magnets M and M^a . When the pick-up circuit for relay N is opened, due to the 40 opening of relay R , relay N will remain closed, due to its holding circuit, until the coil 22 passes over a trackway magnet, at 45 which time a current impulse will be induced in the holding circuit which momentarily neutralizes and reverses the current from battery 17, and so causes relay N to open. This relay will then remain open, 50 due to the fact that its contact 24 is included in the holding circuit.

Relays R and N may be employed to control vehicle governing apparatus of any desired type. As here shown, these relays, 55 together with a circuit controlling device Z , are employed to control a brake application magnet Q which is so arranged as to cause an application of the brakes when the magnet becomes deenergized. The circuit 60 controlling device Z includes an arm 30, which is operated by a centrifugal device (not shown), and which device in turn is driven by a wheel of the vehicle V . When the vehicle is at rest, the arm 30 occupies 65 the position in which it is shown in the

drawing; when the vehicle is in motion, arm 30 moves to the left so that when the speed of the vehicle exceeds 15 miles per hour, this arm passes out of engagement with contact segment 29; when the speed exceeds 35 miles per hour the arm passes out of engagement with contact segment 28; and when the speed exceeds 65 miles per hour this arm passes out of engagement with contact segment 27.

70 When relay R is energized the following circuit for brake magnet Q is closed, provided the speed of the vehicle does not exceed 65 miles per hour: from terminal B of a suitable source of current, through front 80 point of contact 31 of relay R , wire 32, contact 27-30, wire 37 and magnet Q to terminal O of the same source of current. When relay R is open and relay N is closed, 85 brake magnet Q is energized by virtue of the following circuit, provided that the speed of the vehicle does not exceed 35 miles per hour: from terminal B , through the back point of contact 31 of relay R , wire 33, front point of contact 34 of relay N , 90 wire 35, contact 28-30 of circuit controller Z , wire 37, and magnet Q to terminal O . When relays R and N are both open and the speed of the vehicle does not exceed 15 miles per hour brake magnet Q is energized through a circuit which passes from terminal B , through back point of contact 31 of relay R , wire 33, back point of contact 34 of relay N , wire 36, contact 29-30 95 of circuit controller Z , wire 37, and magnet 100 Q to terminal O .

It will be observed that while relay R is closed, the vehicle governing apparatus gives what may be termed a high speed indication, but when relay R is open and relay N is closed, this apparatus gives what may be termed a medium speed indication, and that when both relays are open the apparatus gives what may be termed a low speed indication. As here shown, these indications are given through the medium of brake application apparatus, although it is understood that any other form of apparatus or devices may be employed without departing from the scope of my invention.

110 The operation of the apparatus shown in Figs. 1 and 2 is as follows:

In Fig. 1, I will assume that the vehicle V , which is shown to the left of point A , is equipped with the apparatus shown in Fig. 2. The block to the left of point A is supplied with vehicle governing current from transformer T^a , so that relay R on this vehicle is closed. It follows that as the vehicle V passes point A , the trackway 125 magnet M^a will have no effect on the vehicle-carried apparatus. Block $A-B$ is supplied with vehicle governing current from transformer T^b , so that vehicle V may proceed through this block at 65 miles per 130

hour without incurring an automatic application of the brakes. Owing to the presence of the vehicle governing current in the rails of this block, magnets M and M^a for this block have no effect on the vehicle-carried apparatus. Block B-C is not supplied with vehicle governing current, because track relay H^c for the block next in advance is open. As vehicle V enters block 10 B-C, therefore, relay R will open, thereby causing an automatic application of the brakes unless the engineer has reduced the speed of the vehicle to 35 miles per hour or less. When the vehicle passes trackway 15 magnet M in this block relay N will be opened, so that an automatic application of the brakes will occur unless the engineer has already reduced the speed of the vehicle to 15 miles per hour or less. Trackway 20 magnet M^a at point C will, of course, have no effect on the vehicle carried apparatus, so that vehicle V may enter the occupied block at point C at 15 miles per hour or less.

I will now assume that when the vehicle 25 V is in block B-C, the preceding vehicle V' passes out of the block next in advance. Relay H^c will then close, thereby supplying vehicle governing current to the rails of block B-C, so that relay R on vehicle V 30 will close, thereby permitting this vehicle to immediately resume full speed.

The reason for the trackway magnet M^a at the exit end of each block is to cause a low speed indication on the vehicle at this point 35 if the signal at this point should change to the stop indication after a train has passed the trackway magnet M immediately in the rear.

Referring now to Fig. 3, the apparatus 40 shown herein is similar to that shown in Fig. 2, the only difference being that means are provided for requiring the engineer to acknowledge the caution and stop signals in order to permit the train to proceed at speeds 45 corresponding to the indication given by the signals. The relay R is controlled in the same manner as in Fig. 2, and relay N is also controlled in the same manner as in Fig. 2 with the exception of an additional circuit 50 which will be pointed out hereinafter. The high speed circuit for brake magnet Q is from terminal B of a suitable source of current, through contact 31 of relay R, wire 38, back contact 39 of an auxiliary relay X' , wire 40, contact 27-30, wire 37, and magnet Q to terminal O of the same source of current. This circuit, it will be seen, is closed only when relay R is closed and relay X' open. The medium speed circuit for magnet 55 Q is from battery terminal B, through contact 34 of relay N, wires 43 and 44, contact 45 of an auxiliary relay X^2 , wire 46, contact 47 of relay X' , wire 48, contact 28-30, wire 37, and magnet Q to battery terminal O. 60 This circuit is closed only when relays N, 65

X' and X^2 are closed. The low speed circuit for magnet Q is from battery terminal B, through contact 41 of relay N, wire 42, contact 29-30, wire 37, and magnet Q to battery terminal O. This circuit is closed, it 70 will be observed, only when relay N is energized.

The control of relays X' and X^2 will be explained while describing the operation of the apparatus as a whole. 75

Referring now to Fig. 1, as well as Fig. 3, I will assume that the vehicle V in Fig. 1 is equipped with the apparatus shown in Fig. 3. While this vehicle is in the position shown in Fig. 1, relay R will be closed, because vehicle governing current is supplied to the rails of the block in the rear of point A. Relay X' is open as shown in Fig. 3. It follows, therefore, that the high speed circuit for brake magnet Q will be closed. As 80

vehicle V passes through block A-B no change will occur, because this block is supplied with vehicle governing current, but as the vehicle passes point B, the supply of vehicle governing current is cut off, so that 85 relay R opens. Assuming that the engineer takes no action at this point, it will be seen that the high speed circuit for magnet Q becomes open at contact 31 of relay R and the medium speed circuit of this magnet remains 90 open at contact 47 of relay X' , so that the

low speed limit is immediately imposed upon the vehicle. If, however, just before passing point B the engineer closes push button U', relay X' will be closed, the pick-up circuit being from battery terminal B, through front point of contact 49 of relay R, wire 50, push button U', wire 51, and winding of relay X' to the battery terminal O. 95

As soon as relay R opens, a stick circuit for relay X' is closed, this circuit being from battery terminal B, through the back point of contact 49 of relay R, wire 52, contact 53 of relay X' , wire 54, and winding of relay X' to battery terminal O. Relay X' will, consequently, remain closed as long as relay R is open. Relay X' being closed, the medium speed circuit for magnet Q is closed, so that the vehicle may proceed 100 into block B-C at 35 miles per hour or less without incurring an automatic application of the brakes. Upon passing magnet M in block B-C, relay N will be opened as in Fig. 2, thereby opening both the medium and the low speed circuits for the magnet Q at 105 contacts 34 and 41 respectively. Unless the engineer takes immediate action, the brakes will be applied, regardless of speed, so that the vehicle will be brought to a stop. 110

It will be observed that the medium speed 115 circuit for brake magnet Q is controlled by a contact 45 of a relay X^2 . This relay is energized as long as relay R is closed, the circuit being from battery terminal B, through contact 55 of relay R, wire 56, wire 120

125

57, and winding of relay X^2 to battery terminal O. After relay R opens, relay X remains closed, due to a holding circuit as long as relay N is closed, this holding circuit being from battery terminal B, through contact 34 of relay N, wires 43 and 59, contact 60 of relay X^2 , wires 58 and 57, and winding of relay X^2 to battery terminal O. It will be seen, therefore, that relay X^2 does not 10 open until both relays R and N have opened.

If, therefore, after passing magnet M, the engineer closes push button U^2 , relay N will be closed again by virtue of a circuit which passes from battery 17 through wire 15 65, back contact 64 of relay X^2 , which relay is now deenergized, wire 63, push button U^2 , wires 62 and 20, winding of relay N and wire 61 to battery 17. Relay N will then remain closed, owing to its holding circuit 20 which passes through coil 22. With relay N closed, the low speed circuit for magnet Q is closed, so that the brakes may be released and the vehicle may proceed through the balance of block B-C and into the block 25 next in advance at 15 miles per hour or less.

If the engineer had closed push button U^2 just before passing magnet M, and held it closed while passing the magnet, relay 30 N would have been opened and relay X^2 deenergized, as before, but relay N would be immediately closed again, before the brakes started to apply, by virtue of its pick up 35 circuit through push button U^2 and back contact 64 of relay X^2 , so that an automatic brake application at the location of magnet M would be avoided provided the speed of the train were kept below 15 miles per hour.

Referring now to Fig. 4, the portion of 40 track here shown, is divided into two sections of positive control territory separated by a stretch of non-positive control. By "positive control territory" I mean territory wherein means are provided for supplying the track with vehicle governing alternating current. Each stretch of positive control territory is provided with trackway apparatus which is similar to that shown in Fig. 1, the signals and pole-changers being 45 omitted, however, to simplify the drawing. Located adjacent the entrance end of the non-positive territory is a trackway magnet W, so placed as to be out of alinement with respect to the trackway magnets M and M^2 . 50 As here shown, magnet W is an electromagnet which is constantly supplied with current from a battery 78, although this magnet might equally well be a permanent magnet.

60 Referring now to Fig. 5, the apparatus here shown is particularly adapted for cooperation with the trackway system shown in Fig. 4. This apparatus is the same as that shown in Fig. 2 except that an additional relay Y is provided for the purpose 65

of permitting the vehicle to travel at full speed through non-positive control territory. When relay Y is closed, a high speed circuit for magnet Q is closed, which circuit passes from battery terminal B, through 70 contact 79 of relay Y, wires 80 and 32^b, contact 27-30, wire 37 and magnet Q to battery terminal O. While this circuit is closed, therefore, the vehicle may proceed at 65 miles per hour, regardless of the condition of relays R and M. 75

Relay Y is provided with a pick-up circuit which passes from a coil 67, through wire 68, winding of relay Y, and wire 69 to coil 67. Coil 67 is located on a magnetizable core 66 which is mounted on the vehicle in such position as to pass directly over the trackway cut-out magnet W. As the vehicle enters the non-positive control territory, magnet W will induce current momentarily in the circuit of relay Y, whereupon this relay closes. A holding circuit for relay Y is then closed which passes from battery 70, through wire 71, back contact 72 of relay R, wire 73, contact 74 of relay N, 90 wire 75, contact 76 of relay Y, wire 77, wire 68, winding of relay Y and wire 69 to battery 70. It follows, therefore, that relay Y when once closed will remain closed as long as relay R is open and relay N closed. As soon 95 as the vehicle passes into positive control territory the closing of relay R will deenergize relay Y so that the control of the brakes is restored to relays R and N. If, however, relay R fails to pick up when the 100 train enters positive control territory, relay Y will remain closed until a permanent trackway magnet is encountered, whereupon relay N will open and thus will open the holding circuit for relay Y. If desired, a 105 special trackway magnet M^2 may be provided for this purpose, which magnet is located at the entrance end of the positive control territory. This magnet will cause relay N to open unless relay R is already closed due to 110 vehicle governing current in the track rails. It follows that if the vehicle governing apparatus is out of order when the vehicle enters positive control territory, relay Y will open so that the low speed limit will be imposed on the vehicle. 115

Although I have herein shown and described only a few forms of apparatus embodying my invention, it is understood that various changes and modifications may be 120 made therein within the scope of the appended claims without departing from the spirit and scope of my invention.

Having thus described my invention what I claim is:

1. Railway traffic controlling apparatus comprising track rails divided into sections, means for each section for supplying alternating vehicle governing current to the rails of the section when the section next in ad- 130

vance is unoccupied, a permanent magnet for each section located in the trackway at least at maximum braking distance from the exit end of the section for trains running at medium speed, a continuous control relay on a vehicle, means located on the vehicle and controlled by said vehicle governing current in the track rails for energizing said relay; a medium speed relay on said vehicle, a pick-up circuit for said latter relay controlled by a front contact of said continuous control relay; a holding circuit for said medium speed relay including a front contact of the relay itself, a source of current and a coil in inductive relation to said trackway magnets for neutralizing the effect of said source of current when the vehicle passes over a magnet; and governing means on the vehicle for giving a high speed indication when said continuous control relay is energized, a medium speed indication when the latter relay is deenergized and the medium speed relay is energized, and a low speed indication when both relays are deenergized.

2. Railway traffic controlling apparatus comprising track rails divided into sections, means for each section for supplying alternating vehicle governing current to the rails of the section when the section next in advance is unoccupied, an impulse device for each section located in the trackway at least at maximum braking distance from the exit end of the section for trains running at medium speed, a continuous control relay on a vehicle, means located on the vehicle and controlled by said vehicle governing current in the track rails for energizing said relay, a medium speed relay on said vehicle, means for energizing said medium speed relay while the continuous control relay is energized and for keeping it energized after the continuous control relay becomes deenergized until the vehicle passes over an impulse device, and governing means on the vehicle for giving a high speed indication when said continuous control relay is energized, a medium speed indication when the latter relay is deenergized and the medium speed relay is energized, and a low speed indication when both relays are deenergized.

3. Railway traffic controlling apparatus comprising means for supplying vehicle governing energy to the trackway, permanent magnets located in the trackway, a continuous control relay on a vehicle, means controlled by said trackway energy for energizing said relay, a medium speed relay on the vehicle, a pick-up circuit for said latter relay controlled by a front contact of the continuous control relay, a holding circuit for said medium speed relay including a source of current and a contact of the relay itself and a coil in inductive relation to said trackway magnets for neutralizing the cur-

rent from said source, and governing means on said vehicle controlled by said relays.

4. Railway traffic controlling apparatus comprising means for supplying vehicle governing energy to the trackway, means on a vehicle for giving a high speed or a medium speed indication according to the presence or absence of said energy and impulse devices located in the trackway for causing said vehicle carried means to give a low speed indication in the absence of said trackway energy.

5. Railway traffic controlling apparatus comprising means for supplying vehicle governing energy to the trackway, impulse devices located in the trackway, and means on a vehicle for giving a high speed or a medium speed indication according to the presence or absence of said energy and a low speed indication on passing one of said impulse devices in the absence of such energy.

6. Railway traffic controlling apparatus comprising means for supplying vehicle governing energy to the trackway, impulse devices located in the trackway, a continuous control relay on a vehicle, means controlled by said trackway energy for energizing said relay, a medium speed relay on the vehicle, means for energizing said second relay while the first is energized, and for keeping it energized after the first relay opens until a trackway impulse device is encountered; means controlled by said relays for normally giving a high speed indication when the continuous control relay is energized, a low speed indication when the latter relay is deenergized and the medium speed relay is closed, and a stop indication when both relays are open, and means under control of the engineer for suppressing said low speed indication and causing a medium speed indication to be given instead, and for suppressing said stop indication and causing a low speed indication to be given instead.

7. Railway traffic controlling apparatus comprising a railway having positive control territory and non-positive control territory, means located in the positive control territory for supplying vehicle governing energy to the trackway, impulse devices located in the trackway in said positive control territory, a continuous control relay on a vehicle responsive to the presence and absence of vehicle governing energy in the trackway, a medium speed relay on said vehicle, means for energizing said medium speed relay while the former relay is closed and for keeping it energized after the continuous control relay opens until a trackway impulse device is encountered, vehicle governing means controlled by said relays, a cutout relay on the vehicle having a pick up circuit, means located at the entrance to non-positive control territory for energizing

said pick up circuit, means for holding said latter relay closed while the continuous control relay is open and the medium speed relay closed, and means controlled by said cut-out relay for removing said vehicle governing means from control by said continuous control and medium speed relays.

In testimony whereof I affix my signature in presence of two witnesses.

LLOYD V. LEWIS.
